TOY AUTOMOBILE HOIST

William K. Schauweker, Cleveland, Ohio, assignor
to All Metal Products Company, Wyandotte,
Mich., a corporation of Michigan

Application December 28, 1933, Serial No. 704,212

8 Claims. (Cl. 46—37)

This invention relates to toy automobile hoists and the object of the invention is to provide a telescoping hoist for toy automobiles, trucks or the like, in which the telescoping sections of the hoist are normally expanded by a spring and in which the said sections may be compressed against the tension of the spring by means of a cable and manually rotatable shaft.

Another object of the invention is to provide 10 a toy automobile hoist of the character described having a base on which the telescoping hoist sections are mounted and provided with a shaft rotatably mounted in the base, the telescoping sections of the hoist containing an expanding 15 spring for raising the said sections and a cable being attached to the uppermost section and arranged to be wound on the rotatable shaft to compress the hoist sections against the tension of the spring.

20 A further object of the invention is to provide a rotatable wheel attached to the shaft and provided with diametrically opposite knobs by which the wheel and shaft may be rotated, the wheel being provided with a series of apertures and a 25 catch being provided on the base adapted to engage in the apertures to lock the wheel at any position against the tension of the spring within the hoist sections.

Another object of the invention is to provide 30 a platform having inclined ends and pivotally mounted to turn on a horizontal plane on the uppermost of the hoist sections.

These objects and the several novel features 35 of the invention are hereinafter more fully described and claimed and the preferred form of construction by which these objects are attained is shown in the accompanying drawing in which—

Fig. 1 is a side elevation of the device in the 40 lowered position.

Fig. 2 is a plan view thereof partly broken away to show the operating wheel.

Fig. 3 is an enlarged section taken on line 3—3 of Fig. 1.

45 Fig. 4 is an enlarged section taken on line 4—4 of Fig. 1.

The device comprises a sheet metal base 1 having depending flanges 2 at the sides, as shown in Fig. 4, which are provided with out-turned 50 edges 3 on which the device rests. A bracket 5 is attached to this base 1, as shown in Fig. 3, and the lower hoist section 6 is secured in this bracket, as shown. A second hoist section 7 is provided having an out-turned lug 8 which rides 55 in the slot 9 in the section 6 and the uppermost

hoist section 10 is provided with an out-turned lug 11 riding in the slot 12 of the hoist section 7. These lugs 8 and 11 limit upward or downward movement of the hoist sections and the upper hoist section 10 is provided with a depending tubular portion 13.

The platform 14 shown in Figs. 1, 2 and 3 is formed to provide ways 15 for the wheels of the toy truck and flanges 16 are provided at opposite sides of these ways and extend upwardly, as shown more particularly in Fig. 3. A pin 17 is provided at the center of the platform and extends through a washer 18 beneath the platform and into the depending tubular portion 13 of the hoist section 10 to allow the platform to be 60 turned in a horizontal plane on the hoist.

Connected to the lower end of the portion 13 is a link 18 and a cord or cable 19 is connected to this link and extends through a tube 20 which is secured in the base. A spring 21 for expanding the telescoping sections of the hoist is positioned about the tube 20 at the lower end and extends about the depending tubular portion 13 at the upper end. At the lower end the tube 20 is flared outwardly as shown and the cable 19 extends through this tube and through the base 1 and is wound about a shaft 22 shown in Figs. 1, 3 and 4. This shaft 22 is rotatably mounted in a short tube 23 which is secured in the base 1 and a wheel 24 is secured to the upper end of the shaft, while a circular plate 25 is secured to the lower end thereof. A collar 26 is also secured to the shaft and the cable 19 is wound about the shaft between the collar 26 and the plate 25 and the end 27 of the cable is secured in 80 an aperture in the plate 25 as shown in Fig. 4.

The wheel 24 is provided with a pair of diametrically opposite knobs 28 and is also provided with a series of apertures 29 near the rim of the wheel. Pivotedly mounted on the base 1 in the bracket 30 is a catch 31 provided with a handle 32 at the opposite end. The end 32 of the catch is heavier than the end 31 so that the end 32 tends to drop to the position shown in Fig. 4 by gravity, thus causing the catch 31 to engage in 90 the apertures 29 of the wheel 24.

In the collapsed position, shown in Fig. 1, the toy automobile, truck or other device may be run up onto the platform 14, at which time, by raising the end 32, the catch 31 is disengaged from the apertures 29 in the wheel 24 thus allowing the spring 21 to move the telescoping sections upwardly and raise the automobile and this upward movement of the platform may be stopped at any point by dropping the end 32 100 105 110

of the catch. After the telescoping sections have been expanded, they may be again contracted by grasping one of the knobs 28 of the wheel 24 and rotating the wheel in a clockwise direction in the position shown in Fig. 2. This winds the cable 19 on the shaft of the wheel and compresses the telescoping sections against the tension of the spring 21 and it will be noted in this rotative movement that the apertures in the wheel will readily pass over the end of the catch which is provided with a curved face for this purpose and upon releasing the knobs of the wheel, the catch 31 will prevent reverse rotation of the wheel and will thus prevent the raising of the telescoping sections. As the platform 14 is pivotally mounted in the upper telescoping section, it may be turned to any position desired in relation to the base.

From the foregoing description, it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

1. In a toy automobile hoist, a base, a series of tubular telescoping sections mounted on the base, a coiled spring within said telescoping sections and arranged to normally expand the same, a cable attached to the upper telescoping section and extending through the telescoping sections and base, a shaft rotatably mounted in the base, the cable being secured to the shaft to be wound up on the same, manually operable means for rotating the shaft and latch means normally preventing reverse rotation of the shaft, the said latch means being manually releasable to allow expansion of the telescoping sections by the spring.

2. In a toy automobile hoist, a base, a series of telescoping tubular sections mounted on the base, a coiled spring within said telescoping sections and normally expanding the same, a platform pivotally mounted on the upper telescoping section to turn in a horizontal plane, a cable attached to the upper telescoping section and extending downwardly through the coiled spring and into the base, a shaft rotatably mounted in the base and arranged to be manually rotated, the said cable being secured thereto and arranged

to be wound up on the shaft as the same is rotated, reverse rotation of the shaft allowing the telescoping sections to be expanded by the spring.

3. In a toy automobile hoist, a base, a series of telescoping sections mounted on the base, a platform supported by the telescoping sections, a spring within the telescoping sections normally expanding the same, a cable attached to one of the telescoping sections, a shaft rotatably mounted in the base, a wheel for rotating the shaft, the cable being attached to the shaft to be wound up on the same and latch means normally preventing reverse rotation of the wheel and shaft.

4. In a toy automobile hoist, a base, a series of telescoping sections mounted on the base, means normally expanding the telescoping sections, a cable attached to the uppermost of the telescoping sections and extending through the telescoping sections and base, means on the base for winding up the cable and a latch pivotally mounted on the base and normally preventing unwinding of the cable.

5. In a toy automobile hoist, a base, a series of telescoping sections mounted on the base, a spring within the telescoping sections normally tending to expand the same, a cable connected to the uppermost telescoping section and extending downwardly therethrough and through the base and means on the base for winding up the cable.

6. In a toy automobile hoist, a base, a series of telescoping sections mounted on the base, means normally expanding the telescoping sections, a cable attached to the uppermost of the telescoping sections and extending through the telescoping sections and base and means on the base for winding up the cable.

7. In a toy automobile hoist, a base, a series of telescoping sections mounted on the base, a spring within the telescoping sections normally expanding the same and manually operable means mounted on the base for telescoping the telescoping sections against the tension of the spring.

8. In a toy automobile hoist, a base, a series of telescoping sections mounted on the base, means normally expanding the telescoping sections and manually operable means mounted on the base for telescoping the telescoping sections against said expanding means.

WILLIAM K. SCHAUWEKER.
